(57) **CLAIM**

The ornamental design for a plastic stencil, as shown and described.

DESCRIPTION

FIG. 1 is a perspective view showing my new design;

FIG. 2 is a front elevational view;

FIG. 3 is a right side elevational view;

FIG. 4 is a left side elevational view;

FIG. 5 is a top plan view;

FIG. 6 is a bottom plan view; and,

FIG. 7. Rear elevation view.

The broken lines in the drawings depicting portions of the
plastic stencil are for illustrative purposes only and form no
part of the claimed design.
